UNITED STATES PATENT OFFICE.

FRANCIS GEORGE RAWLING, OF MADISON, WISCONSIN.

PROCESS OF PRODUCING ACETIC ACID.

No Drawing.

Application filed February 12, 1926. Serial No. 87,951.

This invention relates to the production of acetic acid from wood and pertains to a particular process whereby wood is treated chemically to produce the desired acid yielding material while conserving the wood as such and only slightly modified from its original condition.

One feature of the invention is the extraction of acetic acid and acetates from wood by subjecting the wood to the action of chemical materials in aqueous solution at elevated temperatures and pressures.

Heretofore, in the production of acetic acid from wood, it has been customary to employ methods of dry distillation, resulting in the destruction of the wood and leaving the latter as a carbonized residue of low value having little use as a substitute for wood. The present improvement provides a process whereby the wood residues, after the removal of acetic acid, are only slightly altered from the condition of the wood at the time of initial treatment. As contrasted to the previous carbonized residues, the present invention provides for wood residues, which may be used as substitutes for fresh wood in the manufacture of methyl alcohol, ethyl alcohol, pulp, paper and paper products, cellulose and cellulose products and the like, by present known processes.

The several steps of the process of the present invention will now be described. Initially, wood is cut into pieces of convenient size and impregnated with or without the application of vacuum or pressure, or of pressure applied subsequent to the vacuum, in a suitable vessel with an aqueous solution containing sodium sulphite and an alkali or a substance or substances capable of producing an alkali either by hydrolysis or under the conditions of heating to be described, for example, sodium bicarbonate, trisodium phosphate, or sodium sesquicarbonate. A definition which will include sodium bicarbonate and sodium carbonate and salts of suitable alkalinity will be satisfied by the term "sodium salts of weakly ionized polybasic acids", which salts in unimolar solution in water have a P_H number between 11 and 7. Such a definition excludes sodium sulphide and caustic soda. For example, small pieces of wood may be impregnated with an aqueous solution containing four percent of sodium sulphite and six percent of sodium carbonate. The wood may be steamed before treatment with the

chemical solution to assist the impregnation, depending on the condition of the wood. The amount of sodium sulphite to be absorbed by the wood should not be in excess of twenty pounds for each hundred pounds of wood. The sodium sulphites assist in the removal of acetic acid from the wood, without causing the excessive decomposition of the wood substance experienced in other processes such as dry distillation, pulping and acid hydrolysis of wood.

The amount of alkali absorbed in the wood should be sufficient to neutralize enough of the acetic acid formed to prevent the formation of bisulphites in such amount that the latter might tend to decompose the ligno-celluloses according to the recognized action by dissolving the lignin and introducing a large amount of undesirable organic material into the liquid. Since an excess of alkali will also decompose the ligno-celluloses by dissolving the lignin and thus introducing undesirable organic material into the solution, such excess is to be avoided.

To the solution of sulphite and alkali unabsorbed by the wood is withdrawn from the digesting vessel as far as practicable after a period of time, usually one hour is sufficient, and thereafter the digestor and its contained impregnated wood is heated to a temperature of at least 110° C. and not over 160° C. for a suitable period of time, usually not more than six hours. The heating is preferably accomplished by admission of steam. During the heating action, the pressure in the vessel may rise as high as 150 pounds per square inch and the pressure may be released partially from time to time, if found necessary. After the completion of the heating, the contents of the vessel may be removed either under pressure or after the pressure has been released.

The liquid is separated from the solid residue and the latter may be subjected to further treatment by known methods in the manufacture of methyl alcohol, ethyl alcohol, pulp, paper, paper products, cellulose and cellulose products, and the like. The liquid contains acetates in solution, together with other salts and organic material. The solid residue is not greatly changed in appearance from the original wood, and it is not pulped by the heating process.

The separated liquid is rendered acid by the addition of any suitable acid or acid

salt, such as nitre cake or sulphuric acid. The acid liquid is then boiled and the acetic acid is set free and distils off together with water and sulphur dioxide. The vapors are 5 condensed, forming an aqueous solution consisting principally of acetic acid and sulphurous acid. The separated liquid may be treated in a second manner, by making it alkaline by the addition of calcium hydroxide, or lime or other metallic hydroxide, carbonate or bicarbonate, the corresponding sulphite of which is insoluble in water and the corresponding acetate of which is soluble. In this manner, the sulphites present 10 in the separated liquor are precipitated. The liquid after this treatment is separated from the solids present, and is made acid with the addition of a suitable acid or acid salt, preferably sulphuric acid or nitre cake 15 and boiled. The acetic acid is set free and distils, together with water and a small amount of sulphur dioxide. The vapors are 20 condensed, forming an aqueous solution consisting principally of acetic acid and a trace of sulphurous acid.

The condensate from the two methods outlined above can be converted into an aqueous solution of calcium acetate by treatment with lime or calcium carbonate, or into 30 other acetates by neutralizing the solution with the appropriate base, either as hydroxide or carbonate, for example, such bases as lead, magnesium or barium, from which acetic acid and other acetates may be 35 prepared by known methods.

I claim:

1. The process of preparing acetic acid by extraction from wood, which process comprises impregnating wood with a treating material consisting of an aqueous solution of a mixture of sodium sulphite and an alkali, the strength of said treating material being capable of neutralizing acetic acid from the wood but not sufficient to materially affect the lignin content of the wood, subjecting the wood and said treating material to a heat treatment of at least 110° C. and not over 160° C. and thereby forming acetates in solution, rendering the material 40 of the solution acid, and recovering acetic acid from the solution.

2. The process of preparing acetic acid by extraction from wood, which process comprises impregnating wood with an aqueous solution of sodium sulphite and an alkali, the strength of said aqueous solution being capable of neutralizing acetic acid from the wood but not sufficient to materially affect the lignin content of the wood, digesting 45 the wood and the treating material and thereby forming acetates in solution, rendering the material of the solution acid, and recovering the acetic acid from the solution.

3. The process of preparing acetic acid by 50 extraction from wood, which process com-

prises impregnating wood with a treating material consisting of an aqueous solution of a mixture of sodium sulphite and an alkali, the strength of said aqueous solution being capable of neutralizing acetic acid from the 55 wood but not sufficient to materially affect the lignin content of the wood, subjecting the wood and said treating material to a heat treatment of at least 110° C. and not over 160° C. and thereby forming acetates in 60 solution, stopping said heat treatment before the wood is pulped, separating the treating solution from the wood, rendering the solution acid, heating it and distilling off acetic acid from the solution.

4. The process of preparing acetic acid by extraction from wood, which process comprises impregnating wood with a treating material including an aqueous solution of a mixture of sodium sulphite and a salt 65 capable of producing alkali by hydrolysis and which salt in uninolar solution in water has a P_H number between 11 and 7, subjecting the wood in said treating material to a digesting treatment at a temperature of at least 110° C. and not over 160° C., and thereby forming acetates in solution, stopping the digesting action before the wood is pulped, separating the solution from the wood rendering the solution acid, heating 70 the solution and distilling off acetic acid from the solution.

5. The process of preparing acetic acid by extraction from wood, which process comprises impregnating wood with a treating material including an aqueous solution of a mixture of sodium sulphite and a soluble carbonate, subjecting the wood in said treating material to a digesting treatment at a temperature of at least 110° C. and not over 160° C., and thereby forming acetates in solution, stopping the digesting action before the wood is pulped, separating the solution from the wood rendering the solution acid, heating the solution and distilling 75 off acetic acid from the solution.

6. The process of preparing acetic acid by extraction from wood, which process comprises impregnating wood with a treating material including an aqueous solution of a mixture of sodium sulphite and sodium carbonate, subjecting the wood in said treating material to a digesting treatment at a temperature of at least 110° C. and not over 160° C., and thereby forming acetates in solution, stopping the digesting action before the wood is pulped, separating the solution from the wood rendering the solution acid, heating the solution and distilling 80 off acetic acid from the solution.

7. In the process of preparing acetic acid by treatment of wood, the steps comprising digesting wood with a solution consisting of sodium sulphite and an alkali and thereby forming acetates, and thereafter producing 85

acetic acid from said acetates, the strength of said solution being capable of neutralizing acetic acid from the wood but not sufficient to materially affect the lignin content of the wood.

8. In the process of preparing acetic acid by treatment of wood, the steps comprising digesting wood with a solution consisting of sodium sulphite and an alkali and at a temperature of at least 110° C. and not over 160° C. and thereby forming acetates, and thereafter producing acetic acid from said acetates.

9. The process of preparing acetic acid

by extraction from wood, which process comprises impregnating wood with an aqueous solution of sodium sulphite and the sodium salt of a weakly ionized polybasic acid and which salt in unimolar solution in water has a P_H number between 11 and 7, digesting the wood and the treating material and thereby forming acetates in solution, rendering the material of the solution acid and recovering acetic acid from the solution.

In testimony whereof I affix my signature.

FRANCIS G. RAWLING.
